UNITED STATES PATENT OFFICE.

HERBERT F. TURNER, OF CAMBRIDGE, MASSACHUSETTS, ASSIGNOR TO SEARS R. CONDIT, JR., OF BOSTON, MASSACHUSETTS.

SWITCH INTERLOCK.

Application filed January 2, 1920. Serial No. 348,866.

To all whom it may concern:

Be it known that I, HERBERT F. TURNER, a subject of the King of Great Britain, residing at Cambridge, in the county of Suffolk and State of Massachusetts, have invented an Improvement in Switch Interlocks, of which the following is a specification.

In the supply of power for many purposes, such as certain manufacturing processes, lighting, and so forth, it is essential that the supply is not interrupted, or suffers but momentary interruption due to the failure of generating apparatus, or from some other unforeseen happening.

To insure substantial continuity of service, it is common to employ a plurality of sources of power any one of which may be connected to the power supply circuit upon failure of one of the power sources thereby to guard against a protracted interruption of power in the circuit. Usually two independent sources of power which may be remote from each other are adapted to be independently connected to the power supply circuit through separate switches; one of which must always be open so that but one power source at a time is connected to the circuit, the other being connected only upon an emergency.

It frequently happens, however, that, through the carelessness or ignorance of a station attendant, the switch controlling one power source is thrown in while the other power source is connected to the circuit. The usual result is the opening of circuit breakers throughout the system, if not a more extended damage, and, in addition, there is usually a long and serious delay before the error can be rectified and power again restored to the circuit. The usual method of preventing the closing of the wrong switch is by placing a wooden block in the switch mechanism or tying a red tag on the switch handle; but this method is not effective for the block will fall out or be removed and the tag is ignored.

The object of my invention is the provision of an interlock between the switches controlling the connection of the plurality of sources of power to the power supply circuit, whereby when the interlock is set in one position one switch is free to be operated while the other switch is positively locked against operation; and when the interlock is moved to another position the first switch

will be positively locked against operation and the second switch will be free to be operated. I may also so arrange the interlock that in a certain position thereof both switches will be locked against operation.

The means whereby I accomplish this result comprises a bolt extended between the operating mechanism of the switches so constructed and arranged that when moved in one position it positively engages the mechanism of one switch to restrain that switch from operation and is freed from engagement with the mechanism of the other switch to permit the operation of that switch. When moved in the reverse direction it is arranged to lock the first named switch and release the lock on the second switch. When placed in a middle or neutral position it may engage the mechanism of all switches thereby to restrain all switches from operation.

A further object of my invention is to arrange the interlock as an attachment to apply to existing switches for the purpose above set forth.

A further object of my invention is to provide a single switch with a lock by which the switch may be locked against operation and may be unlocked for operation only by the one having the proper key.

A yet further object of my invention is the provision of the interlock with means by which it may be positively locked in any position thereby positively to lock the switches for or against operation as determined by the setting of the interlock.

Fig. 1 is a front view of two switches with which my invention is associated.

Fig. 2 is a plan view of Fig. 1.

Fig. 3 is a side view of one of the switches with the interlock in section, taken along line 3—3 of Fig. 2.

Fig. 4 is a plan section through the switches and interlock along lines 4—4 of Fig. 1.

Fig. 5 is a detail showing the interlock holding and locking means.

Fig. 6 is a modified form of interlock having no neutral position and arranged always to lock or release one switch.

Fig. 7 is a side view of the interlock supporting block.

Fig. 8 is a detail of the lock as applied to a single switch.

As here shown my invention is applied to

the switch mechanisms or switch face plates mounted side by side on the switch board 10. Each face plate 11 and 11^a, has the slot 12 and 12^a therein through which the parallel spaced-apart switch rods 13 and 13^a extend which are pivotally connected to the operating handles 14 and 14^a, pivoted to the face plates at 15 and 15^a. The switches are locked in closed position by the latches 16 and 16^a engaging pins 17 and 17^a and the switches are automatically tripped by the tripping coils 18 and 18^a. The switches may also be manually opened by depressing said pins 17 and 17^a, as is common practice.

15 A block 20 having a central opening 21 into which the slot 22 extends from one side thereof is mounted on the inner side of each face plate and the tube 23 extends between said blocks and has its end received and 20 frictionally retained in the openings therein. Said blocks are secured to said face plates by the bolts 24 extended through the ends of said blocks on each side of said openings 21 therein; and the bolts extended 25 through the slotted ends of the blocks additionally serve to securely clamp said tube to said blocks.

An interlocking bolt 25 is received in said tube 23 and is a sliding fit therein. Said 30 bolt, as more particularly illustrated in Fig. 2, is arranged to engage either one or the other, or both, of said switch mechanisms to lock one or the other, or both, of said switches against operation. For this purpose the inner switch rods 13^a of both switch mechanisms are provided with the locking apertures 30 therein in which the ends of said bolts are adapted to be received when the 35 switch mechanisms are in open position thereby to lock the switches against operation. With the bolt in said apertures it is seen that the switch handles cannot be moved and the switches are therefore, positively restrained in open position.

40 The bolt enclosing tube or casing 23 is formed with an opening or slot 40 therein intermediate its ends and said bolt 25 is provided with a knob or handle 41 by which the bolt may be manually operated to lock 45 the switch. Said slot 40, as in Fig. 1, may be provided with three notches as 40°, 40°, and 40° in which the knob or handle 41 is adapted to be received to be held against unintentional movement. The arrangement 50 is such that when the bolt is so moved as to bring the handle 41 into slot 40° the left hand switch will be locked in open position; in the middle recess 40° both switches will be locked in open position; and in 40° the 55 right hand switch will be locked in open position. The bolt must be partially rotated so as to move the handle out of said notches before the bolt can be axially moved to lock the switches. In Fig. 6 I have shown the 60 bolt enclosing tube as having but two notches

40° and 40° and the bolt is of such a length that it must always lock one and release the other switch.

Means are provided to lock said bolt 25 in any set position so that it cannot be moved from that position to unlock or lock one of the other of the switches except by one having the proper key. Said means comprises the plate 50 having the slot 51 therein which is pivoted to a second plate 52 secured to the switch board 10.

The hook 60 of a padlock is adapted to be extended through said slot 51 to pass around and engage the handle 41 of said interlock bolt thereby to positively lock said bolt in 80 any of the notches of said tube 23, when the padlock is unlocked and removed the plate 50 falls downward by gravity away from said handle and the interlock bolt is thereby free to be moved.

In the modification shown in Fig. 8, the lock is applied to a single switch. In this modification the tube 60 has aligned apertures therethrough and the bolt 65 has a hole therethrough which in the locked-open 90 position of the switch is adapted to align with the apertures in said tube. A pin 66 is extended through the aligned apertures in said tube and bolt and the hook of a padlock 80 is extended through a hole in the end of said pin thereby to lock the pin against withdrawal whereby the switch is positively locked in open position.

95 It is obvious that other methods of locking the switch and the interlock may be employed without departing from the spirit of my invention.

100 I claim:

1. An electric switch having a movable member formed with a locking aperture, a stationary member, a locking-bolt movably carried thereby arranged to be moved manually into and also out of the aperture in said movable member to lock said movable member against or unlock it for operation and means to lock said locking bolt against movement to said stationary member in both positions of said locking bolt.
2. An electric switch having a face-plate, a switch-operating rod associated therewith having a locking-member receiving aperture, said face-plate having an apertured lug, and a manually operable locking bolt slidably received in the aperture of said lug arranged to be moved manually into and also out of the aperture in said operating rod to lock said rod against or unlock it for operation and means to lock said locking bolt in rod-locked and also rod-unlocked positions thereof.
3. The combination of two switches having independent switch-operating mechanisms, and manually operable locking means associated with and manually movable independently of said mechanisms in one di-

rection to engage and lock one of said mechanisms, and in the other direction to engage and lock the other mechanism.

4. The combination of two switches having independent switch-operating mechanisms, and manually operable locking means associated with and manually movable independently of said mechanisms in one direction to engage and lock the first mechanism and release the second mechanism, and in the other direction to engage and lock the second mechanism and release the first mechanism.

5. The combination of two independently operable electric switches, manually-operable locking means movable independently of said switches into one position to lock one of said switches against operation and into an intermediate position to lock both switches against operation and into a third position to unlock the first switch and hold the second switch locked against operation.

6. The combination of two independently operable electric switches, manually-operable locking means movable independently of said switches into one position to lock one of said switches against operation and into an intermediate position to lock both switches against operation and into a third position to unlock the first switch and hold the second switch locked against operation, and means to hold said manually operable means in set position.

7. The combination of two electric switches having independent switch-operating mechanisms, each mechanism having a bolt-receiving portion, a locking bolt extended between said mechanisms arranged for manual movement independently of said mechanisms to selectively lock said mechanisms against operation, and bolt-supporting means in which said bolt is slidably received.

8. The combination of two electric switches having independent switch-operating mechanisms, each mechanism having a bolt receiving portion, a locking bolt extended between said mechanisms manually movable independently of said mechanisms selectively to engage and lock one mechanism and disengage and unlock the other mechanism, and means to restrain said bolt in any set position.

9. The combination of two electric switches each having a face plate, an operating handle pivoted on each face plate, a switch operating rod connected with each handle extended through a slot in its face plate, each rod having a locking aperture therein, and a locking bolt supported on said face plates

between said rods arranged to be moved manually independently of said operating rods into or out of the apertures in said operating rods to lock said switches selectively in open condition.

10. The combination of two electric switches having independent switch-operating mechanisms, each mechanism having a bolt receiving portion, a tube extended between said mechanisms, supporting means therefor, a locking bolt slidably received in said tube manually movable into locking engagement with said mechanisms, said tube having a notched slot therein, and said bolt having a knob removably received in said notches thereby to restrain said bolt in set position.

11. The combination of two electric switches having independent switch-operating mechanisms, each mechanism having a bolt-receiving portion, a tube extended between said mechanisms, supporting means therefor, a locking bolt slidably received in said tube manually movable into locking engagement with said mechanisms, said tube having a notched slot therein, and said bolt having a knob removably received in said notches thereby to restrain said bolt in any set position, and means to lock said bolt in set position.

12. An attachment for a pair of electric switches, each switch having a face-plate through which switch-operating mechanism extends, comprising a tube having supporting means at its ends engageable with the face plates for its support, a locking bolt slidably received in said tube manually movable into locking engagement with the switch mechanisms, said tube having a notched slot therein, and said bolt having a knob removably received in one of the notches whereby said bolt is restrained in set position.

13. An attachment for a pair of electric switches, each switch having a face-plate through which switch-operating mechanism extends, comprising a tube having supporting means at its ends engageable with the face-plates for its support, a locking bolt slidably received in said tube manually movable into locking engagement with the switch mechanisms, said tube having a notched slot therein, and said bolt having a knob received in one of the notches whereby it is restrained in set position, and a stationary member to which said knob is adapted to be locked.

In testimony whereof, I have signed my name to this specification.

HERBERT F. TURNER.
